UNITED STATES PATENT OFFICE.

GEORGE W. VREELAND AND GEORGE E. WISENER, OF STEUBENVILLE, OHIO.

REMOVAL OF BLAST-FURNACE SALAMANDERS.

Application filed September 1, 1921. Serial No. 497,494.

To all whom it may concern:

Be it known that we, GEORGE W. VREELAND, and GEORGE E. WISENER, both citizens of the United States, and residents of Steubenville, in the county of Jefferson and State of Ohio, have invented certain new and useful Improvements in the Removal of Blast-Furnace Salamanders, of which the following is a specification.

10 This invention relates to the removal of the salamander which forms on the hearths of blast furnaces during the time the furnaces are in blast, and more particularly relates to handling the salamanders in the removal thereof.

One object of the invention is the remotion of the salamanders in a highly novel manner, whereby salamanders are quickly removed from the furnace in an effective and economical manner, wherein the necessity of cutting or breaking the salamander into pieces or lumps is avoided and overcome, and wherein the necessity of recourse to the use of dynamite or other high explosives or to 25 the use of the electric arc or oxy-acetylene or oxy-hydrogen flame in removing the salamanders is prevented and made unnecessary.

A further object of the invention is the provision of improved means for handling 30 and disposing of the material forming the salamander in the remotion thereof, and still further objects of the invention will become apparent upon examination of the drawing and detailed description and by reference 35 to the appended claims in the following specification.

Referring now to the drawing, forming part of this specification, Figure 1 is a sectional elevation showing the hearth and 40 bosh of a blast furnace, as preferably equipped preparatory to blowing in the furnace in readiness for later use when occasion demands, as for example, when preparing for relining the furnace.

45 Figure 2 is a similar sectional elevation of the furnace hearth and bosh, illustrating the condition of the furnace hearth at the end of the life of the furnace lining, with the salamander as formed therein during the 50 time the furnace is in blast.

In the accompanying drawing, the numeral 2 designates the foundation on which the cylindrical wall 3 of the furnace hearth or well 4 is supported. The upper end of the 55 hearth wall 3 supports the upwardly and

outwardly inclined bosh wall 5 of the furnace.

The furnace is provided with the usual complement of tuyère openings 6, an opening at a lower level, forming the cinder notch 7 and at a still lower level, close to the bottom of the hearth or well 4, is the tapping hole or iron notch 8 through which the molten iron flows when the furnace is tapped in the ordinary casting operations, during 60 the time the furnace is in blast.

By reference to Figure 2, it will be seen that the refractory bottom of the hearth or well of Figure 1, which is shown as built in Figure 1, had disappeared, and a large 70 cavity has formed in the bottom of the hearth below the level of the tapping hole 8 which is constantly filled with molten metal during the time the furnace is in blast, this pool of metal forming what is known as the 75 "salamander."

As shown in Figure 1 an opening, normally closed or sealed by a refractory plug 9, is formed in the foundation of the hearth or well 4 when the furnace is being built or relined, the opening being located at a point which will approximate the bottom of the salamander formed in the hearth while the furnace is in operation. The provision of this opening and the plug 9, when building 80 or relining the furnace, facilitates a breach being easily and quickly made in the hearth wall by drilling or otherwise so as to form a hole 9^a, as shown in Figure 2, and enables the metal to be run out into sand-beds or 85 ladles, as will be hereinafter more fully pointed out.

It is, of course, to be understood that the provision of the hole and its plug 9^a is desirable but not absolutely necessary in order 90 to carry out our invention, as a hole for the remotion of the salamander may be formed in the hearth wall of existing furnaces.

The upper face of the bottom of the furnace well or hearth is usually adjacent to or 100 but a short distance below the level of the iron notch or tapping hole 8, through which the molten iron is tapped during the time the furnace is in blast, as is shown in Figure 1.

105 The life of the refractory lining of a blast furnace extends over a considerable period of time, usually a matter of years, and during the time the furnace is "in blast" erosion of the refractory bottom of 110

the well or hearth 4 causes a cavity to form and gradually deepen, so that the bottom of the furnace well or hearth eventually becomes lowered to a point very considerably 5 below the level of the furnace tapping hole or iron notch 7.

The result is that when the furnace is 10 blown out, for relining, a large pool of molten metal remains in the depression or cavity formed in the hearth 4 below the level of the furnace tapping hole 7 during the iron making campaign of the furnace.

Heretofore it has been the universal practice to allow this pool of metal, termed the 15 "salamander" to solidify in place and, after it cools to solidification, to break up and remove the salamander, in chunks or pieces of considerable size.

Two ways of breaking up and removing 20 the salamanders have been employed heretofore. It is still the practice, and for many years was the only known method, to first drill blast holes in the salamander with air or steam drills and to then break the salamander into pieces small enough to handle, by means of dynamite or other high explosive. This operation is not only very slow and laborious but also is extremely dangerous, it frequently being the cause of serious and 25 even fatal accidents to workmen, and almost invariably resulting in damage to surrounding property by flying pieces of salamander, and forms a large part of the cost of preparing the blast furnaces for relining.

30 Of recent years the well known oxygen flame has been used in cutting or boring the holes formed in the salamander to receive the explosives, instead of the air or steam drills formerly employed.

35 When the salamander is of very great size (sometimes the salamander will weigh as much as 300 tons), the difficulties accompanying its removal by the old methods are correspondingly increased, and frequently 40 part of the salamander is allowed to remain in place, on account of the great amount of trouble and the expense connected with its removal. In such cases the masonry forming the bottom of the furnace hearth is built 45 over and around the portions of the salamander remaining in place.

We have devised a simple and effective 50 method of removing the salamander from blast furnace hearths, whereby the dangers and difficulties of the old methods are entirely obviated, the time required is greatly lessened, and the cost is very materially reduced.

55 The invention consists in the remotion of the salamander from the well or hearth of the furnace after the furnace is blown out and before the molten metal forming the salamander has cooled enough to solidify.

60 The removal of the salamander is effected by cutting or drilling a hole 9^a through the

foundation of the furnace, which opens into the cavity containing the salamander, as near as possible to the bottom of the salamander, and then draining off the molten metal forming the salamander, through 70 this hole or opening. The above method will be used with existing furnaces now in blast by forming a breach in a suitable location in the hearth wall. When relining the furnace or building a new furnace, an 75 opening preferably will be built into the furnace at about the level experience teaches the bottom of the salamander will reach during the years the furnace will remain in blast, and this opening will be closed with the refractory plug 9, a good grade of fire brick being used as a lining for the hole and in forming the plug, which will be carefully built therein when constructing the furnace lining. The provision of the 80 plugged opening or hole, as will be readily understood, will lessen the time and trouble necessary when the hole is afterward opened in order to remove a salamander in accordance with our improved method.

85 Provision will be made to drain off the molten iron forming the salamander into ladles, or into a temporary pig bed, which will be constructed in a suitable location at the side of the furnace. In an emergency, the iron of the salamander can be allowed 90 to flow over the surrounding ground, and to spread over a large surface, so as to form a relatively thin sheet which, when cooled, can be easily and quickly broken up into 100 pieces of small size which are easily handled manually.

95 The advantages of our invention will be appreciated by those skilled in the art, and modifications in the way in which our invention is carried out may be made without departing from the invention as defined in the appended claims.

105 We claim:—

110 1. In the remotion of blast furnace salamanders, the step which consists in draining the metal forming the salamander from the furnace hearth through a breach formed in the hearth wall for that purpose before the molten salamander has cooled to solidification.

115 2. In the remotion of blast furnace salamanders, the steps consisting in forming a breach in the furnace hearth wall at a point adjacent to the bottom of the salamander, 120 and draining the metal forming the salamander from the furnace hearth through said breach before the molten salamander has solidified.

125 3. The method of removing blast furnace salamanders which consists in forming a hole in the hearth of the furnace in building the hearth, maintaining a seal in said hole while the furnace is in blast, and removing the seal from said hole to drain 130

off the molten salamander, in the remotion thereof after blowing out the furnace.

4. The method of removing blast furnace salamanders which consists in forming a tapping hole in the hearth of the furnace, at a point approximating the bottom of the salamander, in building the hearth, sealing said hole while the furnace is in blast, and removing the seal to drain off the molten salamander from the hearth.

5. The method of removing blast furnace salamanders which consists in forming a

tapping hole in the hearth of the furnace, at a point approximating the bottom of the salamander, in building the hearth, sealing 15 said hole while the furnace is in blast, and removing the seal to drain off the molten salamander from the hearth, and running the drawn off metal into suitable receptacles, in the removal thereof.

In testimony whereof, we have hereunto set our hands,

GEORGE W. VREELAND.
GEORGE E. WISENER.
